IGNITION SYSTEM

James O. Johnston, St. Petersburg, Fla., assignor
to City Fuel Oil and Coal Company, St. Peters-
burg, Fla., a corporation of Florida

Application October 12, 1940, Serial No. 361,005

2 Claims. (Cl. 158—91)

This invention relates to methods of and an apparatus for igniting oil burners particularly of the natural draft pot type.

It is an object of my invention to provide an electric ignition system for pot type oil burners of high efficiency and of such simplicity in construction as to be readily adaptable for manufacture and installation at low cost.

In starting of the burner operation in oil burners of the type noted, numerous difficulties in the past have been experienced in the preliminary stages of combustion in vaporizing the oil and mixing the same with oxygen in the air sufficiently to support combustion. Therefore it is an object of my invention to provide an improved ignition system, including in an oil burner a heating element and improved means and methods of introducing a stream of air directed in the form of a sheet or curtain surrounding the heating element and directed and concentrated immediately upon the in-flowing oil.

Another object of my invention is to provide a novel method of rapid ignition by the introduction of an auxiliary air supply so directed as to scatter the ionized path passing between the ignition electrodes causing the succession of sparks forming the heating element and passing between the ignition electrodes to cover a wider area, increasing the pressure of the air at the arc and the size of the spark pattern.

Another object of my invention is to provide means whereby upon the temperature of the burner being raised to a predetermined degree the auxiliary air supply introduced to increase the size of the spark area will be cut off thereby resulting in the spark pattern resuming its normal size until the ignition circuit is broken.

Another object of my invention is to provide means for regulating the stream of auxiliary air whereby upon the temperature of the burner being raised to a point sufficient to generate the oil supply into gas so as to maintain normal operation of the burner, the stream of air aforesaid will be cut off and the burner operation carried on in the conventional manner having the air supplied through openings provided in the wall of the burner.

Another object of my invention is to provide for a pot type oil burner, an electric ignition system of such simplicity in construction as to be arranged to operate with high efficiency without the use of a mechanical atomizing device and with or without the use of an oil attenuated wick pad, and which may be readily attached to an oil burner of the type noted.

Another object of my invention is to provide in an oil burner an ignition system which for its successful operation does not require a supply of air under high pressure or a forced draft, but which is rather adapted to operate at a high efficiency with natural draft air.

With the above and other objects in view, which will appear as the description proceeds, the invention resides in the methods, combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings which form a part of this specification, like characters of reference indicate like parts in the several views, wherein:

Figure 1 is an assembly view partly in elevation and partly in section of a burner embodying an ignition system constructed in accordance with my invention.

Figure 2 is a view of the wick pad taken along the line 2—2 of Figure 1 and looking in the direction of the arrows.

Figure 3 is an enlarged longitudinal vertical section of my ignition apparatus shown in Figure 1.

Figure 4 is an enlarged side elevation of my ignition apparatus illustrated in Figure 1.

Figure 5 is an end view of the air nozzle of the ignition apparatus taken along the line 5—5 of Figure 3 and looking in the direction of the arrows.

Figure 6 is a longitudinal vertical section of a modified form of my invention showing the pattern assumed by the succession of sparks passing between the ignition electrodes when the control valve of the auxiliary air supply is open and the air directed around and through the arc.

Figure 7 is a fragmentary view of Figure 6 showing the pattern assumed by the succession of sparks passing between the ignition electrodes when the control valve of the auxiliary air supply is closed.

Figure 8 is a fragmentary view of the thermostatic control means illustrating the operation of the mercury switch shown in Figure 6.

To carry out my invention there is provided as shown in Figure 1 a burner 1 of the pot type, well known in the art, having an outlet opening 3 in the top thereof. The side walls of the said burner have provided as indicated by numeral

4 a plurality of suitable apertures for the purpose of supplying air in the proper quantities to support combustion of the oil gases generated in the normal operation of the burner from the oil supply indicated by numeral 6. The latter oil supply is introduced in the burner 1 through the conduit 21.

The particular structure of the burner, however, forms no part of the present invention except in so far as it cooperates therewith. My invention is concerned primarily with means and methods of starting the burner operation in the preliminary stages of combustion.

In accordance therewith, my ignition apparatus comprises as shown in Figure 3 the horizontally extending tubular sleeve or conduit 7 having provided at one end the curved tubular air nozzle 8 and at the opposite end the vertically extending tubular portion 9 forming connecting air passages. The tubular sleeve 7 and the air nozzle 8 are arranged so as to project into the burner 1 through an aperture 10 suitably positioned in the side wall near the bottom of the said burner.

The nozzle 8 is directed downwardly with the mouth or opening 11 thereof positioned immediately above the oil supply 6 carried by the bottom of the burner 1 and the oil attenuated wick pad 35 as shown by Figures 1 and 3.

The vertical extension 9 of the tubular sleeve 7 has the lower end 12 thereof closed while the upper end 13 is open having a valve seat 14 adapted to cooperate with a valve member 15. The valve member 15, Figures 4 and 5 is carried by an adjustable bolt 16 secured by the adjustment nut 17 to one end of the bimetallic strip 18. The opposite end of the said bimetallic strip 18 is suitably fastened at 20 to the upper end of the supporting member 19 which at the lower end is in turn fastened to the closed lower end 12 of the vertical extension 9. Formed integral with the tubular sleeve 7 are provided, the laterally projecting flanges 22 carrying the screw threaded bolts 23 adapted to engage screw threaded holes suitably provided in the side of the burner 1, whereby the ignition apparatus may be securely fastened to the said burner.

My ignition apparatus further includes a heating element assembly comprising an electrical conductor 24 mounted preferably in a porcelain insulating member 25. The insulating member 25 is securely mounted in the fastening collars 26 and 27.

The threaded fastening collar 26 is engaged in a screw threaded aperture 28 suitably provided in the side of the vertical extension 9 of the tubular sleeve 7, while the screw threaded collar 27 is adapted to engage the screw threaded opening 29 provided in the end of the collar 26. The insulating or supporting member 25 is disposed in suitable openings provided in the two collars 26 and 27. The said member 25 has formed integral therewith at the mounted end thereof, the annular flange 30 which is adapted to be clamped between an inner part of the fastening collar 26 and the end of the collar 27 which as previously described is screw threadedly engaged at 29 in the collar 26. The member 25 is thus securely mounted in the collars 26 and 27.

The member 25 projects from the said mounting across the vertical tubular extension 9 into the tubular sleeve 7, where the said member 25 extends in parallel relation to and equally dis-

tanced from the side walls of the said sleeve 7. The member 25 is further curved downwardly to the mouth 11 in parallel relation to the side walls of the nozzle 8 and is centrally positioned with respect to the mouth 11.

Secured to the end of the conductor 24 is the circular disc like metal baffle 31 mounted in front of the opening 11 of the nozzle 8 as shown in Figures 4 and 5.

At the opposite end of the conductor 24 engaging the screw threaded end thereof is the adjustable nut 32 adapted to fasten to the conductor 24 the electrical cable 33 representing one wire of the supply circuit for the heating element, the other wire of the supply circuit being grounded to the bottom of the burner 1. Any suitable source of electrical energy may be used, and it will, of course, be understood that proper transformers and high tension spark coils and suitable switches for the heating element will be used in the supply circuit. They are not illustrated, as any standard construction will suffice.

Further, mounted on the bottom of the burner 1 is the metal strap or bar 34 having the opposite ends thereof grounded by being welded to the bottom of the said burner. The said strap 34 is adapted to securely hold in place a wick pad 35 formed preferably of asbestos.

Moreover the strap or bar 34 serves as one electrode of a spark gap while the disc 31 serves as the opposite electrode of the spark gap or arc utilized as the heating element in the embodiment of my invention shown in Figures 1 to 5 inclusive.

In starting the burner operation by means of my improved ignition system previously described the oil is first fed to the burner by means of the conduit 21.

The wick pad 35 positioned adjacent to the inlet opening of the conduit 21 will draw a portion of the oil up by capillary action attenuating the said oil in a manner well known in the art.

Moreover the valve 15 being in open position, a stream of air will pass through the opening 13 and out the mouth 11 of the tubular nozzle 8. The air entering the valve opening 13 may be under any suitable pressure, but I have found that for successful operation it may be merely natural draft air.

The baffle or circular disc 31 mounted at the opening 11 of the nozzle 8 will deflect the air flowing from the mouth 11 of the nozzle 8 in the form of a curtain or sheet surrounding the arc between the electrodes 31 and 34. Since the mouth 11 of the nozzle 8 is positioned immediately above the wick pad 35 and the same is directed downward, this curtain like stream of air will not be immediately diffused in the burner but will be directed and concentrated upon the attenuated oil held by the wick pad 35. Now upon a suitable electric current being supplied through the conductor 24 to the electrode 31 and through the bottom of the burner 1 to the grounded electrode 34 as previously explained, there will be caused an electric spark or arc to pass between the electrodes 31 and 34 generating heat, by means of which the volatilized oil or oil gases mixed with the air oxygen immediately adjacent to the said heating element will become ignited. The resultant combustion will in turn generate further heat which together with the inflowing air stream aforesaid will cause further volatilization of the remaining oil and the rapid combustion thereof until the

burner is operating at the maximum efficiency.

Upon the burner becoming heated to a predetermined degree the increased temperature will cause the bi-metallic strip 18 to bend gradually downward as the temperature increases causing the valve 15 to gradually close the valve opening 16 until it rests upon its seat 14 shutting off the air directed through the air nozzle 8. It will be understood that, in gravity pot burners of this type, the pot is formed with the correct number of openings in its sides to supply the requisite amount of air to produce proper combustion. Any additional air introduced at the low point or bottom of the burner during normal operation would upset the balance, producing objectionable results such as a yellow, noisy or distorted flame. For this reason it is desirable to provide the above described thermostatic valve, to shut off the additional air supply when the burner heats up and is in full operation. When the fire goes out, and the burner cools, the valve will open again to admit the additional air needed for ignition, as above explained.

However, upon the valve opening 13 being completely closed by the thermostatic action aforesaid, the heat generated by the burner and the air supplied through suitable apertures 4 will be sufficient to support normal combustion of the oil gases in the burner.

Moreover, the temperature at which the valve 15 will close may be conveniently regulated by adjusting the screw 11 on the bolt 16 thereby lowering or raising with respect to the seat 14 the valve 15 held by the bolt 16.

In the embodiment of my invention illustrated in Figure 6 there is provided a burner 51 of the pot type, as previously described, having suitable air holes 52 in the wall thereof for the purpose of supplying air to support combustion in the normal burner operation. The numeral 54 indicates generally the oil supply carried on the bottom of the burner 51 and introduced through the conduit 53.

The modified form of my ignition apparatus disclosed in Figure 6 comprises the tubular sleeve or conduit 55 which projects downwardly into the burner 51 at an acute angle to the bottom thereof, having the lower end 56 of the said sleeve 55 open. The said sleeve 55 is inserted into the burner 51 through the aperture 57 suitably provided in the side wall of the said burner near the bottom thereof.

Mounted at the upper end of the said tubular sleeve 55 is provided the vertical tubular extension 58 forming a connecting air passage to the tubular sleeve 55.

The upper end 59 of the vertical extension 58 is open having a valve seat 60 adapted to cooperate with the valve 61 when in closed position.

Fastened to the vertical extension 58 by welding or in any suitable manner is the vertically projecting arm 62 having fastened at the upper end thereof the casing 63 in which is housed the electromagnet 64 which controls the valve 61.

The valve 61 has mounted thereon the vertically extending valve stem 65 slidably disposed in the recess 66 provided in the core 67 carrying the windings of the electromagnet 64.

The excitation of the winding of the magnet 64 is controlled by the thermostatic bi-metallic strip 68, the terminals 69 and 70 of the electromagnet 64 being connected as shown in Figure 6 in circuit with a thermostatic switch of the mercury type comprising the sealed envelop 75 of tube like shape provided with a pair of elec-

trodes 71 and 72 sealed into it upon one side and containing a quantity of mercury indicated at 74. The said envelop is horizontally mounted at one end on the bi-metallic strip 68 by the supporting conductor arm 13.

The terminal 69 of the electromagnet 64 is connected in any suitable manner to the electrode 71 while the terminal 70 of the electromagnet 64 is connected to one terminal of a suitable electric supply circuit. The opposite terminal of the electric supply circuit is grounded through the burner to the electrode 72.

The electrode 72 is suitably connected to the bi-metallic strip 68 by means of the supporting arm 13 and the lower end of the bi-metallic strip 68 is suitably fastened to the raised part 16 provided on the side of the burner 51 and is thereby electrically grounded to the said burner.

The upper end of the tubular sleeve 55 has provided the screw threads 17 adapted to engage the screw threaded collar 18 in which is suitably mounted the insulating member 19 preferably formed of porcelain. The member 19 has mounted therein one end of the electrical conductor 80 which extends in the tubular sleeve 55 in parallel relation to and equally distanced from the side walls of the said sleeve.

The conductor 80 projects from the mounting 19 downwardly in the tubular sleeve 55 into the burner 51. The upper part of the sleeve 55 which projects in the said burner at an acute angle to the sides thereof is positioned immediately above the end of the conductor 80.

Mounted on the bottom of the burner 51 and positioned immediately beneath the lower end of the conductor 80 is the metal strap 81 mounted adjacent to the inlet port of the oil conduit 53. The opposite ends of the said strap 81 are grounded by welding the same to the bottom of the said burner.

The upper end of the conductor 80 has provided the adjustment nut 82 whereby the electric cable 83 representing one terminal of a suitable electric supply circuit may be conveniently connected to the conductor 80. The opposite terminal of the said supply circuit is grounded to the bottom of the burner 51.

The conductor 80 and the strap 81 will then upon the closing of the electric circuit aforesaid form opposite electrodes of a spark gap which may be conveniently regulated by adjusting the collar 18 on the screw threads 17, thereby raising or lowering the electrode 80 with respect to the electrode 81.

In the operation of the modified form of my invention illustrated in Figure 6, oil is first fed to the burner by means of the conduit 53. Then with the break points 71 and 72 of the mercury switch closed by the mercury as shown in Figure 6, the electromagnetic force of the magnet 64 will hold the valve 61 in an open position.

A stream of air which may be merely natural draft air will then pass through the opening 59 into the tubular sleeve or conduit 55 and out the lower opening 56 surrounding the electrode 80 and the arc formed between the electrodes 80 and 81 increasing thereby the air pressure at the arc. Moreover, since a large proportion of the said inflowing air will strike the oil supply 54, carried on the bottom of the said burner, at an acute angle behind the arc the said air stream will be deflected by the said oil into the arc aforesaid causing a scattering of the ionized path formed between the ignition electrodes, resulting

in the arc or succession of sparks passing between the electrodes assuming a wide spark pattern or area as illustrated in Figure 6.

Thus upon a suitable electric current being supplied to the said electrodes, the heat generated by the wide pattern spark gap or arc will cause the volatilized oil or oil gases mixed with the air oxygen and the said arc, or adjacent thereto, to become ignited.

Accelerated by the angle at which the inflowing stream of air is directed by the tubular sleeve 55, the ignition aforesaid of the oil gases will be rapidly spread over the oil supply 54 igniting further oil gases which will in turn generate additional heat causing further volatilization of the remaining oil, thereby bringing the burner operation rapidly to maximum efficiency.

Upon the burner becoming heated to a predetermined degree the increased heat generated in the burner will cause the bi-metallic strip 68 to bend away from the burner 51 as shown in Figure 8 inclining the mercury switch so as to cause the mercury 14 under the force of gravity to break contact with the electrode 72 thereby opening the electric circuit aforesaid causing the electromagnet 64 to release the valve 61 permitting the valve 61 and valve stem 65 under the force of gravity to slide downward closing the valve opening 59 with the valve 61 resting on the valve seat 60.

Upon the valve opening 59 being closed as aforesaid, the air holes 52 will suffice to support the normal combustion of the oil gases in the burner. For the purposes of comparison, Figure 7 illus-

trates the limited spark pattern which results between the electrodes 80 and 81 upon the closing of the valve opening 59, and the ignition circuit remaining closed.

It is to be understood, however, that while the employment of an electric arc or spark gap is illustrated and described as the heating element; other forms of heating elements may be used such as for example, a hot wire heating element or devices of similar nature.

Having thus described my invention, what I claim as my invention and desire to secure by Letters Patent is:

1. In a liquid fuel burner of the pot type having means for supplying liquid fuel onto the bottom of the burner; ignition means comprising a pair of spaced electrodes providing a spark gap; a tubular conduit positioned to deliver into the said burner a stream of flowing air surrounding the said spark gap, a valve controlling the flow of air through said conduit, and thermostatic means governing the position of said valve, said thermostatic means being so constructed and arranged as to close said valve when the burner heats up to a predetermined temperature, and open said valve only when the fire is out and the burner is cold, thus providing an additional supply of air at the time of ignition.
2. A liquid fuel burner as set forth in claim 1, in which the thermostatically controlled valve is electromagnetically operated, whereby it closes instantly when the critical temperature is reached.

JAMES O. JOHNSTON.
